UNITED STATES PATENT OFFICE.

HENRY HIGGINS, OF CHORLTON-CUM-HARDY, NEAR MANCHESTER, ENGLAND,
ASSIGNOR TO JOHN WILKINSON AND ALFRED WILKINSON, OF MAN-
CHESTER, ENGLAND.

PHOTOGRAPHIC-PRINTING FRAME.

SPECIFICATION forming part of Letters Patent No. 673,522, dated May 7, 1901.

Application filed February 20, 1901. Serial No. 48,134. (No model.)

To all whom it may concern:

Be it known that I, HENRY HIGGINS, a subject of the King of Great Britain and Ireland, residing at 15 Maple avenue, Chorlton-cum-Hardy, near Manchester, in the county of Lancaster, England, have invented new and useful Improvements in Photographic-Printing Frames, of which the following is a specification.

10 This invention relates to an improvement in photographic-printing frames such as are employed for taking copies from a negative.

15 The object of this invention is to enable an examination to be made of the paper that is being printed from the negative in order to note the progress of the work without the paper moving from its position on the negative, and thereby preventing the print or copy being blurred, which is of frequent occurrence 20 in ordinary printing-frames, in which the back is made in two halves or parts, each of said halves or parts being connected by hinges and each part retained in the frame by a spring-band or the like, that presses the back 25 onto the negative with the paper to be printed between. When one part of the cover is raised to examine the progress of the work, the relative positions of the negative and the paper that is being printed are frequently 30 changed by a slight movement of the other portion of the back, causing the print to be imperfect.

35 By my present invention I effectually prevent either backward, forward, or lateral movement of the back when one half or part is loosened for examination of the work and the relative positions of the negative and the print are accurately maintained until completed.

40 In the accompanying drawings, illustrating my said invention, Figure 1 is a plan view of the frame with the back fixed therein. Fig. 2 is a longitudinal section on line A A. Fig. 3 is a like section with the back removed. 45 Fig. 4 is a plan of the back. Figs. 5 to 8 are details drawn to an enlarged scale.

In the views similar letters refer to similar parts.

a is a printing-out frame.

b is the back or cover.

50 At a given point within each of the sides a^x of the frame, preferably in the center, I form a vertical groove c , which I line with a metal plate d or a plate of other hard substance which is produced from a thin piece 55 of material by pressing or stamping so as to form corrugations, as shown in Fig. 5, which is an edge view of said plate. The center corrugation d' is formed to fit accurately in the vertical groove c in the side of the frame. 60 The flat portions d^x of the plate on each side of the central corrugation lie against the side surface of the frame, and the turned-in edges d^2 are pressed and dovetailed into slits in the side surface of the frame. The plate is there- 65 by firmly fixed to the frame. I extend the outer ends e of the hinge-pins sufficiently to insert in the aforesaid grooves, the length of the extension and the diameter of the pins being such that they will fit accurately in the 70 grooves, but may be higher or lower therein vertically, according to the thickness of the negative and the print.

I claim as my invention—

1. A photographic-printing frame having 75 a back of two halves, hinges to secure them together, said hinges having pins extending on their outer sides, in combination with the frame proper having on its inside edges grooves to receive and hold the extending 80 pins of the hinges to hold either half of the frame when the other half is turned on the hinges, substantially as described.

2. A photographic-printing frame having 85 a back of two halves, hinges to secure them together, said hinges having pins extending on their outer sides, in combination with the frame proper having inserted plates provided with grooves, in which the extending pins of the hinges are adapted to fit snugly, as and for 90 the purpose described.

In testimony whereof I have signed my name to this specification in the presence of two subscribing witnesses.

HENRY HIGGINS.
